UNITED STATES PATENT OFFICE.

MILTON H. BALLARD, OF LYNN, MASSACHUSETTS, ASSIGNOR TO TRIPP FRUIT WRAPPING MACHINE CO., OF SAN FRANCISCO, CALIFORNIA, A CORPORATION OF MAINE.

WRAPPING-MACHINE.

No. 906,483.

Specification of Letters Patent.

Patented Dec. 8, 1908.

Application filed April 6, 1907. Serial No. 366,656.

To all whom it may concern:

Be it known that I, MILTON H. BALLARD, of Lynn, county of Essex, State of Massachusetts, have invented an Improvement in 5 Wrapping-Machines, of which the following description, in connection with the accompanying drawings, is a specification, like characters on the drawings representing like parts.

10 This invention relates to wrapping machines of the type represented in Letters Patent #516,136, dated March 6, 1894, and in my application for Letters Patent filed February 9, 1906, #300,331, and particularly to 15 the printing-device for printing the web of paper which is fed forward and severed to form the wrappers.

The object of my invention is to provide a printing apparatus, whereby an electrotype 20 or other form of printing plate, as contrasted with a rubber stamp, may be employed, and the web of paper printed at a particular part thereof, so that when subsequently severed to form a wrapper the printing will occupy a 25 certain position thereon. Also, to provide means for adjusting the printing apparatus with respect to the paper, so that it will operate to print the paper at different points, to provide for forming from the web of paper 30 wrappers of different lengths, with the printing centrally disposed on the wrappers.

My invention comprehends the employment of a web printing apparatus and means for moving it with respect to the paper, and 35 means for operating the printing-mechanism to print the paper, while the apparatus is being moved along and the paper is held at rest; also the employment of means for adjusting the printing-apparatus with respect 40 to the paper.

Figure 1 shows in side elevation a sufficient portion of a wrapping machine embodying my invention to illustrate the same. Fig. 2 is a plan view of the parts shown in 45 Fig. 1. Fig. 3 is a side view of the printing-apparatus and means for operating it. Fig. 4 is a vertical sectional detail taken on the dotted line 4—4 Fig. 1. Fig. 5 is a detail showing the frame of the printing-apparatus 50 and its operating shaft. Fig. 6 is an enlarged side view of the printing-apparatus, the frame being shown in vertical section. Fig. 7 is a vertical longitudinal section of the printing-apparatus. Fig. 8 is a detail of the

means for operating one of the inking rolls. 55 Fig. 9 is a detail to be referred to.

41, 42 represent a pair of feeding-rolls for the paper, which are adapted to be operated intermittently to feed forward predetermined lengths of paper for the wrappers. The two 60 feeding-rolls 41, 42 are geared together at one end, so that one of the rolls may be used to drive the other roll. To the lowermost roll 42 which is employed as the driving roll, a clutch-member 60 is secured, and a clutch- 65 member 61 is provided, which is movable into and out of engagement with said member 60 and which is also rotatable. The clutch-member 61 is connected with or secured to a spiral gear 64, which is engaged 70 and driven by a spiral gear 65, secured to a shaft bearing a pinion 53, which is engaged by a rack-bar 54, connected by a link with an upright arm 55, pivoted, at its lower end, to the frame, and which has extended from it, 75 at or near its lower end, a curved slotted extension, to which is adjustably connected one end of a bar 57, which is connected by an eccentric to the main shaft f^5 . As the shaft f^5 revolves the rack-bar 54 is reciprocated longitudinally and the pinion is reciprocated rotarily and the spiral gear 65 likewise reciprocated rotarily and the spiral gear 64 is moved along on its support and is also rotated, to thereby move the clutch-member 61 into engagement with the fixed clutch-member 60, and to rotate it, to rotate the feed-roll 42. By changing the connection of the bar 57 with the slotted extension the length of stroke of the rack-bar may be varied in order 90 that the feed-rolls may be operated to feed forward a greater or less length of paper to provide for the production of wrappers of different lengths or sizes. The feed-rolls, however, may be operated by any other 95 means, as far as my present invention is concerned, or in lieu thereof any other means may be employed for intermittently feeding the paper.

The web of paper which is fed forward by 100 the feeding-rolls is severed to form the wrappers, and, as herein shown, 306 represents a cross-head which carries the knife, the opposite ends of which are connected by links 310 to a pair of arms 312, secured to a rock-shaft 105 313, and an upright rod 70 is connected to one of said arms 312, which is moved up and down to thereby rock the shaft and move the

arms and raise and lower the cross-head. The lower end of the rod 70 is connected to one end of a lever 71 pivoted at 72, the opposite end of which is connected to the lower 5 end of a rod 73, the upper end of which is engaged by a cam secured to the driving shaft f^6 . The knife may be raised and lowered by any other means, so far as my present invention is concerned, or in lieu thereof any other 10 means may be employed for severing the paper to form the wrapper.

The printing-device for the paper, as herein shown, consists of a web printing apparatus; and means are provided for moving it 15 with respect to the paper, while the paper is at rest. 1 represents the main frame of the printing-apparatus, which consists of a box-like structure, constructed and arranged to provide bearings for the operating parts. 2 20 represents the type-cylinder and 3 the impression-roll. The impression-roll is journaled in a yoke 4, which is pivoted at 5, and which is yieldingly held down by a spring arranged in a suitable support.

25 The inking-apparatus for the type cylinder comprises inking-rolls 7, 8, 9, 10, 11, 12 and 13 of usual construction and an ink-reservoir 14.

A toothed gear 15 is secured to the shaft 30 of the type-cylinder, which is engaged by a pinion 16, engaged and driven by a toothed gear 17, secured to a shaft bearing a spiral gear 18, which is engaged and driven by a spiral gear 19, splined on the shaft 20, and 35 which is free to move back and forth thereon. The shaft 20 has secured to it a bevel-gear 21, which engages a bevel-gear 22, secured to the shaft f^6 . The pinion 16 also engages and drives a toothed gear 23, secured to the 40 shaft of the inking-roll 8, and another toothed gear 24 on said shaft engages a pinion 25 secured to a shaft 26. A cam is also secured to said shaft 26, which is adapted to operate the ink-spreading rolls, 9, 10 and 11, the actuating levers for said rolls 9 and 11 being 45 connected together and the actuating levers for the rolls 10 and 11 having laterally extended pins, which enter a groove or grooves in said cam. The shaft 26 also has secured

50 to it a cam 28, see Fig. 8, which is adapted to move a frame 29, bearing the inking-roll 12, so as to move said roll into engagement with the ink-roll 13, a spring, which is connected to said frame, operating to move said roll in 55 the opposite direction, out of engagement with said roll 13 and into engagement with the inking-roll 8. The shaft 26 also bears an arm 30, which, during each revolution thereof, engages a star wheel 31, secured to the 60 shaft of the ink-roll 13, for the purpose of intermittently rotating said roll. As the shaft f^6 revolves the several coöoperating parts of the printing-mechanism are caused to rotate and to otherwise operate.

65 The type-cylinder 2 is provided with a

type-plate 110 of any suitable width but of a length to extend but part way around the cylinder, so that during a part of the revolution of the cylinder the paper will be printed, and during the remainder of the revolution 70 the paper will be disengaged in order that it may be moved along by the paper feeding-device.

When the type-plate disengages the paper the impression-roll 3 will not act to press the 75 paper down onto the type-cylinder for the reason that an adjustable stop-pin 32 will strike the frame and thereby limit its downward movement.

As it is designed and intended that the 80 printing-mechanism shall print the paper, while the paper is at rest, the entire printing-apparatus is made movable with respect to the paper, and is adapted to operate to print the paper while moving along; and, thereafter, while the type-plate disengages the paper the printing-apparatus is returned to its normal position, preparatory to again moving along and printing the paper. To provide for thus reciprocating the printing- 90 apparatus it is provided with rolls 33, any suitable number being employed, which are arranged to run on a pair of tracks 34, which are provided on the frame.

To reciprocate the printing-apparatus a 95 pinion 35 is secured to the shaft f^6 , which engages an internally toothed rack 36, having an arm 37 extended from it, which is pivotally or otherwise connected to the frame of the printing-apparatus. The rack 36 has an 100 ear 38 on its lower edge, which extends downward and which has a rib 39, projected from it laterally, which is adapted to engage a pin 40. As the pinion 35 revolves the rack is moved first in one direction and then in the 105 opposite direction and the rib moves along first above the pin 40 and then below said pin, the rack thereby rising at the completion of its stroke in one direction and falling at the completion of its stroke in the other direction. It is obvious, however, that other means than that herein shown may be employed for reciprocating the printing-apparatus.

The distance traveled by the printing-apparatus in each direction, corresponds to or 115 is at least as great as the length of the type-plate, so that while moving in one direction the type-plate will engage and print the paper, and while moving in the opposite direction will return to its normal position during which time the paper is fed forward. And the movement of the printing-apparatus and the speed of the type-cylinder are so 120 regulated that while the apparatus is moving along, carrying the type-cylinder with it, said cylinder will roll along on the paper which is at rest and will print the same without wrinkling or otherwise injuring it.

125 Adjustment is provided for the printing- 130

apparatus by which it may be caused to occupy different positions with respect to the paper, so as to print the paper at the proper place in order that when the paper is severed 5 the printed portion will occupy a central position on the severed portion or wrapper; and such adjustment is necessary to provide for printing the paper so as to thus centrally dispose the printing on the severed portions 10 or wrappers of different sizes. To accomplish this result the printing apparatus is adjustably connected with the means employed for moving it back and forth. This adjustment does not vary the extent of movement 15 of the printing apparatus, but merely varies the positions of the printing-apparatus relative to fixed points at the beginning and end of its movement.

The means employed for moving the printing-apparatus back and forth are connected 20 to a bar 80 and the printing-apparatus is adjustably connected with said bar. As herein shown, the arm 37 is loosely connected to said bar 80, and said bar is shaped to fit a 25 dovetailed or other shaped recess in the frame of the printing-apparatus, so that said frame may be moved along on said bar 80, and to hold the frame fixed in any position it may be set on said bar 80, a sliding-block 81, 30 see Fig. 9, is fitted in a diagonally arranged hole in the frame of the printing-apparatus, which is movable toward and from the bar 80 by means of a hand-screw 82 or other suitable means. Thus, to adjust the printing- 35 apparatus the hand-screw will be loosened and the printing-apparatus then moved along with respect to the bar 80, to the desired point, and then said hand-screw will be tightened and the printing-frame thereby 40 secured to the bar 80. Thus, in the operation of my device, the paper is first moved forward while the type-plate disengages it, and the printing-apparatus is returned to its normal position or starting point, and then, 45 while the paper is at rest, the printing-apparatus is moved in the opposite direction with respect to the paper and the printing-mechanism thereof operates to print the paper.

Having thus described my invention, what 50 I claim as new and desire to secure by Letters Patent is:—

1. In a wrapping machine, the combination of intermittently operated means for feeding a web of paper, means for severing 55 it, a web printing apparatus, means for moving it back and forth and means for operating the printing-mechanism continuously, substantially as described.

2. In a wrapping machine, the combination of intermittently operated means for feeding a web of paper, means for severing it, a web printing apparatus, means for moving it with respect to the paper, and means for operating the printing mechanism continu- 60 ously, substantially as described.

3. In a wrapping machine, the combination of intermittently operated means for feeding a web of paper, means for severing it, a web printing apparatus, means for moving it in one direction while the paper is held at 70 rest and for returning it while the paper is moved forward, and means for continuously operating the printing-mechanism, while it is being moved back and forth, substantially as described. 75

4. In a wrapping machine, the combination of intermittently operated means for feeding a web of paper, means for severing it, a web printing apparatus, comprising rotary printing-mechanism and a reciprocating 80 frame bearing it, means for reciprocating said frame and means for continuously operating the printing-mechanism while the frame reciprocates, substantially as described. 85

5. In a wrapping machine, the combination of intermittently operated means for feeding a web of paper, means for severing it, a web printing apparatus having a rotary type-cylinder, a rotary impression roll, a rotary inking-mechanism, a reciprocating frame bearing said parts, a spline shaft, a gear thereon for driving the printing-mechanism continuously, and means for reciprocating said supporting-frame, substantially 90 95 as described.

6. In a wrapping machine, the combination of intermittently operated means for feeding the paper, means for severing it, a web printing apparatus having a rotating 100 type-cylinder bearing a type-plate, means for moving said printing-apparatus back and forth, a distance as long as the length of the type-plate, while the paper is held at rest, substantially as described. 105

7. In a wrapping machine, the combination of intermittently operated means for feeding the paper, means for severing it, a web printing apparatus having a rotating type-cylinder bearing a type-plate, means for moving said printing-apparatus back and forth, a distance as long as the length of the type-plate while the paper is held at rest, and means for rotating said type-cylinder at a certain speed corresponding to the speed of 110 the moving apparatus, whereby the type-plate is caused to roll along on the paper, substantially as described. 115

8. In a wrapping machine, the combination of intermittently operated means for feeding a web of paper, means for severing it, a web printing apparatus, means for moving it back and forth relative to the paper, to which it is adjustably connected and means for operating the printing-mechanism continuously, substantially as described. 120 125

9. In a wrapping machine, the combination of intermittently operated means for feeding a web of paper, means for severing it, a web printing apparatus comprising rotary 130

printing-mechanism, a reciprocating frame bearing it, and means adjustably connected with said frame for reciprocating it, substantially as described.

5 10. In a wrapping machine, the combination of intermittently operated means for feeding a web of paper, means for severing it, a web printing apparatus, comprising rotary printing - mechanism, a reciprocating frame 10 bearing it, an internal rack connected with

said frame, a pinion engaging said rack, and means for continuously revolving said pinion, substantially as described.

In testimony whereof, I have signed my name to this specification, in the presence of 15 two subscribing witnesses.

MILTON H. BALLARD.
